UNITED STATES PATENT OFFICE.

CHARLES REINEKE, OF NEW YORK, N. Y.

INTERNAL-COMBUSTION ENGINE.

Application filed October 1, 1920. Serial No. 414,048.

To all whom it may concern:

Be it known that I, CHARLES REINEKE, a citizen of the United States, residing at New York, in the county of New York and 5 State of New York, have invented certain new and useful Improvements in Internal-Combustion Engines; and I do hereby declare the following to be a full, clear, and exact description of the invention, such as 10 will enable others skilled in the art to which it appertains to make and use the same.

This invention relates to internal combustion engines, and more particularly to the type of multi-stroke engine set forth in 15 my co-pending application Serial Number 396,902, filed July 17, 1920.

An object of the present invention is to produce a novel power transmitting mechanism wherein the reciprocating movement 20 of the pistons is converted into a relatively slow rotary movement by the interpositioning of gearing.

Another object of this invention is the production of a multi-stroke internal combustion engine in which the relatively rapid reciprocating movement of the pistons is transmitted to a power shaft in a smooth 25 and positive manner and without the interpositioning of the usual crank.

30 A further object of the invention is to produce a multi-stroke engine having opposed pistons and means for synchronizing the movements of opposite pistons in adjacent cylinders for evenly transmitting 35 the power from said piston to a relatively slow moving shaft.

A further object of the invention is to provide a simple and easily constructed engine wherein advantages of assembling, 40 repair and low cost of production are important factors.

With these and other objects in view my invention further consists in the construction and arrangement of the several parts 45 hereinafter described and pointed out in the appended claims.

In the accompanying drawings, in which corresponding reference characters designate similar parts in the several views:

50 Figure 1 is a vertical sectional view through my improved engine;

Figure 2 is a vertical transverse sectional view;

55 Figure 3 is a horizontal sectional view on the line 3—3 of Figure 2; and

Figure 4 is a fragmentary view illustrat-

ing another form of gearing capable of transmitting power.

The present invention has been designed with a view to obtaining a simple and direct 60 transmission of the reciprocatory movement of the pistons to a power shaft. In marine internal combustion engines, for example, it is desirable to obtain a relatively slow speed of the propeller shaft as compared 65 with the high speed piston travel and to this end I have applied to my multi-stroke motor, a positive form of interconnected gearing for transmitting steady and maximum power. It will be understood, however, that my engine is equally applicable 70 to other uses of either stationary or mobile character, such for example, as heavy duty power generating plants, automobiles and the like. It will be further understood that 75 oil, compressed air, steam and other power mediums may be employed, and various other changes made in the design and construction of my engine to provide for these several motive agents, and I do not limit 80 myself to the exact disclosures herein shown and described.

Referring to the drawings, in which I have shown for example a two cylinder type of engine, the base 1 may be of any design, 85 to which are secured at 2 the cylinders 3.

Operable within the cylinders 3 are opposed pistons 4 and 5, between which the fuel charge is admitted and fired in any 90 approved manner. The fuel charge may be forced into the cylinders by means of auxiliary or crank case compression, and any approved type of valve control for the inlet and exhaust of said charges through ports 7 and 8, may be provided as will be 95 understood.

The lower pistons 5 are each provided with freely revolvable rollers 10 designed to operate between cooperating arms or wings carried by cam elements 11 and 12. 100 Frame sections 9 are connected to the upper piston 4 and are provided with rollers 10' designed to operate between cooperating arms or wings of the cam elements. As shown, each cam element is formed with four arms or wings, but it will be understood that this number may be varied to increase or decrease the number of strokes of the engine.

110 In operation it will be seen that as the pistons 4 and 5 are separated, the rollers 10 carried by the lower piston 4 will move or

- scissor downwardly between the cooperating arms of the cam elements 11 and 12; and the rollers 10' carried by the frame sections 9 connected to the upper pistons will move 5 or scissor upwardly between other of said cam elements, thereby revolving the same in opposite directions, and causing the shafts 13 and 14 to which the cam elements are secured, to rotate.
- 10 The intermediate shaft 14 is journalled in bearings 15 provided on cross webs of the base 1. A worm 16 is secured to the shaft 14 and is designed to mesh with a worm gear 17 secured to a vertically disposed shaft 18, journalled in suitable bearings 19. To the lower end of the shaft 18 is secured another worm 20 adapted to mesh with a worm gear 21 secured to the main or power shaft 22 of the engine.
- 15 The shafts 13 are arranged upon each side of the intermediate shaft 14, and are journalled in bearings 23 provided on other cross webs of the base 1.
- 20 Worms 24 are secured to each shaft 13, and are designed to mesh with respective worm gears 25 secured to vertically disposed shafts 26. To the ends of the respective shafts 26 are secured other worms 27 which are adapted to mesh with worm gears 28 secured to the main or power shaft 22.
- 25 It will be obvious that these respective sets of separated mechanisms are right and left arrangements of worm gearing interconnected as shown upon opposite sides of the main shaft 22, thereby serving to evenly balance the thrusts and associated movements of the several parts.
- 30 It will also be apparent that the opposite rotation of the cam elements and their supporting shafts is changed by the aforesaid gearing to a single direction of rotation in the main or power shaft 22.
- 35 In the form of gearing shown in Figure 4, wherein a series of ordinary spur gears is utilized, the respective shafts 13 and 14 are each provided with a single gear of a different size. For example the large gear 29 is secured to the shaft 14, and is adapted to mesh with a similar gear 30 carried by the
- 40 main shaft 22. The associated shaft 13 has secured thereto a relatively smaller gear 31 designed to mesh with an interposed idler gear 32, which latter in turn meshes with a similar gear 34 secured to the main
- 45 shaft 22.
- 50 From this construction it will be seen that the opposite rotations of the shafts 13 and 14 are directly converted by this form of interposed gearing so that the driven main
- 55 shaft 22 rotates in a single direction.
- 60 Any type of mechanism can be connected to the main shaft 22 as will be understood.
- 65 The means for synchronizing the opposite pistons of adjacent cylinders comprises a connection 35 suitably guided in a sleeve 36,
- and having its respective ends connected to the lower piston 5 in one cylinder at 37 and the upper piston 4 in an adjacent cylinder at 38. By this construction the pistons are kept in timed relation and are prevented 70 from dropping or setting in an uneven manner when the engine is stopped.
- From the foregoing it will be obvious that I have produced a highly efficient and easily driven motor, the reciprocating piston 75 travel of which is both reduced and converted so that relatively low but maximum driving power of the main shaft is obtained.
- 1 claim:
1. In an internal combustion engine the combination with a cylinder of opposed pistons arranged therein, a power shaft, and means interposed between said pistons and power shaft whereby a multiplicity of power strokes of the pistons is required for effecting a single revolution of the power shaft, said means including oppositely moving cams cooperatively associated with said pistons and a gearing connecting the cams to the power shaft for driving said power shaft. 80
  2. In an internal combustion engine the combination with a cylinder of opposed pistons arranged therein, a power shaft, and means interposed between said pistons and power shaft whereby a multiplicity of 85 strokes of the pistons is required for effecting a single revolution of the power shaft, said means including oppositely revolvable cams cooperatively associated with said pistons and a series of gears operatively connected with said cams for driving the said power shaft. 90
  3. In an internal combustion engine the combination with a cylinder of opposed pistons arranged therein, a power shaft, and means interposed between said pistons and power shaft whereby a multiplicity of 95 strokes of the pistons is required for effecting a single revolution of the power shaft, said means including oppositely revolvable cams, shafts for said cams, and a series of gears interposed between the said shafts and the aforesaid power shaft for driving the same. 100
  4. In an internal combustion engine the combination with a cylinder of opposed pistons arranged therein, a power shaft, and means interposed between said pistons and power shaft whereby a multiplicity of 105 strokes of the pistons is required for effecting a single revolution of the power shaft, said means including oppositely revolvable cams, shafts for said cams, and a series of 110 gears interposed between the said shafts and the aforesaid power shaft for driving the same. 115
  5. In an internal combustion engine the combination with a cylinder of opposed pistons arranged therein, a power shaft, and means interposed between the said shafts and the aforesaid power shaft for driving the same. 120
  6. In an internal combustion engine the combination with a cylinder of opposed pistons arranged therein, a power shaft, and means interposed between the said shafts and the aforesaid power shaft for driving the same. 125
  7. In an internal combustion engine the combination with a cylinder of opposed pistons arranged therein, a power shaft, and 130

means interposed between said pistons and power shaft whereby a multiplicity of strokes of the pistons is required for effecting a single revolution of the power shaft, 5 said means including oppositely revolvable cams and associated rollers, and gears interconnected with said cams and the aforesaid power shaft.

6. In an internal combustion engine the combination with a cylinder of opposed pistons arranged therein, a power shaft, and means interposed between said pistons and power shaft whereby a multiplicity of strokes of the pistons is required for effecting a single revolution of the power shaft, 10 said means including cams having oppositely revolvable radial arms, rollers adapted to operate between the said arms, and a series of gears interposed between said cams and the power shaft.

7. In an internal combustion engine the combination with a cylinder, of a plurality of pistons arranged therein, a power shaft, and means interposed between said power 15 shaft and the aforesaid pistons whereby a

multiplicity of strokes of the pistons is required for effecting a single revolution of the power shaft, said means including oppositely revolvable cams, and two series of meshing gears for transmitting the motion 30 from the oppositely revolvable cams to the power shaft.

8. In an internal combustion engine the combination with a cylinder, of a plurality of pistons arranged therein, a power shaft, 35 and means interposed between said power shaft and the aforesaid pistons whereby a multiplicity of strokes of the pistons is required for effecting a single revolution of the power shaft, said means including oppositely revolvable cams, and two series of worm gears for transmitting the motion 40 from the oppositely revolvable cams to the power shaft.

In testimony whereof I affix my signature, 45 in presence of two subscribing witnesses.

CHARLES REINEKE.
